DESIGN FOR A BUILDING

Herbert J. Sandin and Howard H. Hait,
McKeesport, Pa.

Application October 10, 1939, Serial No. 87,613

Term of patent 14 years

To all whom it may concern:

Be it known that we, Herbert J. Sandin and Howard H. Hait, citizens of the United States of America, residing at McKeesport, in the county of Allegheny and State of Pennsylvania, have invented a new, original, and ornamental Design for a Building, of which the following is a specification, reference being had to the accompanying drawings, wherein:

We claim:

The ornamental design for a building, as shown.

HERBERT J. SANDIN.

HOWARD H. HAIT,
